WET SPINNING FRAME

William McL. Fraser, Stonington, Conn., assignor
to Atwood Machine Company, a corporation of
Connecticut

Application October 31, 1940, Serial No. 363,691

6 Claims. (Cl. 57—35)

This invention relates to a spinning frame of that type usually referred to as a wet spinning frame; and has for one of its objects to provide an arrangement of the frame whereby the same effective functions of the frame may be obtained with the occupation of less area or floor space, thus enabling a greater number of frames to be placed into a given floor space for operation.

A more specific object of the invention is to so arrange a frame that it will be narrower in width than frames of similar capacity and construction heretofore made.

Another object of the invention is to provide for a greater flexibility of control of the liquid applied to the yarn prior to its spinning.

Another object of the invention is to improve the view of the yarn.

A more specific object of the invention is to apply liquid to the yarn rather than immerse the yarn in the liquid itself.

With these and other objects in view, the invention consists of certain novel features of construction, as will be more fully described, and particularly pointed out in the appended claims.

In the accompanying drawings:

Fig. 1 is a sectional view largely diagrammatic, looking endwise of the machine equipped with my invention;

Fig. 2 is a fragmental sectional view on a larger scale, illustrating the container for the liquid which is applied to the yarn;

Fig. 3 is a diagrammatic view of the drive for the liquid-applying roll; and

Fig. 4 is a fragmental view, illustrating an adjustment for the rods which carry the supporting brackets.

In a wet spinning frame of this character it has been usual to mount the container for the liquid to be applied to the yarn at approximately the same horizontal level as, or just below, the nip rolls, and back of the nip rolls which hold the twist being put in the yarn. The container for the liquid is of considerable breadth and requires the frame to be of substantial width in order that the liquid container may be accommodated; and in order to make the frame of narrower construction and retain all of the effectual advantages of a frame of this character, I have elevated the liquid-containing trough and placed the nip rolls and supply package beneath portions of the trough, whereby I am able to make a frame of much less width and yet one which is fully as efficient functionally as the previous machine which occupies a greater amount of space.

Further, by this arrangement I have been able to convey the yarn across the top of an applicator roll whereby I may both govern the extent of contact of the yarn with the roll and by the speed of the roll, govern the amount of liquid applied to the yarn; and further, by arranging this applicator roll at about eye level the observation of its action may be more readily observed; and the following is a more detailed description of the present embodiment of this invention, illustrating the preferred means by which these advantageous results may be accomplished:

With reference to the drawings, the framework consists of a main desk, designated 10, with legs 11 extending downwardly therefrom. Packages of twisted yarn are designated 12, suitably supported on spindles driven through the whorls 13 by belts 14 engaging driving drums 15 extending the length of the frame with an individual take-up pulley 16, all mounted upon suitable framework 17 of the machine. There is a ring rail 18 and ring 19 through which the yarn 20 is delivered to the package 12, the same being guided through the thread board guide 21 extending from the thread board 22 and then by a ring traveler on the ring, all of which may be movable from a suitable builder motion guided by rods 23 and bosses 24. This is all usual construction of the frame.

Nip rolls 25 and 26 are mounted in a stand 27 which is supported upon the deck 10, while just rearwardly of these nip rolls there is located a supply package of yarn 28. An upright standard 29 is supported upon the deck 10 and extends to a sufficient height to support the trough 30 clear above the supply package 28. This trough contains a liquid 31 such, for instance, as oil, which is to be applied to the yarn prior to its being twisted between the nip of the rolls 25 and 26 and the ring traveler which guides the yarn about the package 12.

This liquid trough assembly is of considerable lateral dimension (see Fig. 2) and comprises a casting 33 which extends from one upright standard 29 on one side of the machine to another upright standard 29 on the other side of the machine, while a suitable pan 30 extending lengthwise of the machine removably rests upon and is supported between such laterally-extending brackets or castings 33 located at spaced intervals along the machine. Driven applicator rolls 34 are supported in bearings from the castings 33 and positioned to revolve partially immersed in the liquid 31 to pick up the liquid and apply it to the yarn. Pig-tail yarn guides 36 are mounted

in bars 38 for guiding the yarn 39 on one side of the roll while brackets 60 mounted on rods 61 support rods 37 carrying pig-tail guides 35 on the other side of the roll through which the yarn 39 extends so as to contact the roll 34 and receive therefrom the liquid to be applied to the yarn. The liquid-applying mechanism above described for one side of the frame is duplicated on the other side of the frame, the frame of course being the usual back-to-back arrangement of operating parts.

This arc of contact may be governed by an adjustment of the pig-tail guides. The bars 37 on either side of the machine carried by the bracket 60 may be adjusted by rotation of the rods 61 upon which these brackets are mounted by means of the clamp screws 62, there being segmental gears 63 meshing with each other so that the rods 61 will be simultaneously rotated such, for instance, as through segment 64 mounted on one of the rods 61 and worm 65 having crank 66. These gears may be mounted at one end of the frame for manual manipulation. After rough adjustment of the pig-tail guides 35 is thus accomplished, finer adjustment may be had by screwing either one of the pig-tail guides 35 or 36 more or less into the bars which support them. The thread on each guide is of such a fineness that one complete turn or several complete turns will be utilized for such adjustment. The bars carrying the pig-tail guides may have a traverse motion where desired.

The rolls 34 are driven, and the speed of rotation of these rolls will also vary the amount of liquid picked up and applied to the yarn; that is, if the rolls are driven fast, more liquid would be picked up and applied to the yarn than if they were driven slow. This speed may be governed at the head end of the machine where the gear box is located, there being a drive gear 50 and a driven gear 51 on the end of the shaft for rolls 34 with a change gear 52 for the purpose of securing the desired rotation of the rod shaft.

It will be apparent that as the yarn 39 is led from the supply package, it will extend upwardly over the guide bar 48, thence through the inner guide 36 over the roll 34 and through the front guide 35; thence forwardly over guide 41 through pig-tail guide 42 about the lower nip roll 28 between the rolls 26 and 25; and thence through the traveler 19 on the ring 18 and to the package 12. Rotation of the package will draw the yarn through the traveler and will place the desired twist in the yarn.

A standard 45 extends upwardly from the bracket 33 with pins 46 projecting in either direction; thus, fresh supply packages 47 or empty bobbins or completed work may be placed upon these pins for convenient storage until it is desired to use the same.

By the arrangement which I have just described, the broad liquid-containing trough assembly is elevated so that a very narrow deck 10 may be provided, and thus the entire width of the machine reduced.

Further, the yarn which travels from the supply package through the moistening device is so arranged that the amount of moisture to be applied to the yarn may be very readily adjusted and yet a large amount of storage due to the

pins located above for receiving the supply, empty bobbins, or finished packages, may be had.

The foregoing description is directed solely towards the construction illustrated, but I desire it to be understood that I reserve the privilege of resorting to all the mechanical changes to which the device is susceptible.

I claim:

1. In a wet spinning frame, a trough for liquid to be applied to the yarn, a roll revolvable in said liquid, guides for the yarn on either side of said trough to cause the same to contact said roll at least tangent thereto, all of the guides on one side of the roll being supported on a common bar and means to adjust said bar to simultaneously adjust the guides on one side of the roll.

2. In a wet spinning frame, a trough for liquid to be applied to the yarn, a single roll revolvable in said liquid, guides for the yarn on either side of the roll to cause the yarn to contact said roll at least tangent thereto, all of the guides on one side of the roll being supported on a common bar, means to adjust said bar to simultaneously adjust the guide secured thereto, and means to drive the roll to govern the amount of liquid applied to the yarn.

3. In a wet spinning frame, a main deck, legs to support the same, nip rolls for controlling the point of yarn twist supported by said deck and above the same, a yarn supply also supported by said deck, laterally extending brackets, a trough for containing liquid to be applied to the yarn supported on said brackets, an upright standard supporting said brackets at a height substantially above said rolls and yarn supply, and means for storing the bobbins supported by said brackets.

4. In a wet spinning frame, nip rolls for controlling the point of yarn twist, a yarn-supply package supported at substantially a common horizontal level with said rolls and laterally spaced therefrom, and a liquid-applying means for the yarn occupying a greater lateral space than the said lateral space between said rolls and the said package and located at a height and position to overlie said lateral space.

5. In a wet spinning frame, nip rolls for controlling the point of yarn twist, a yarn-supply package supported at substantially a common horizontal level with said rolls and laterally spaced therefrom, and a liquid-applying means for the yarn occupying a greater lateral space than the said lateral space between said rolls and the package and located at a height and position to overlie said lateral space and overlie a portion of said rolls and liquid-applying means.

6. In a wet spinning frame, a main deck, legs to support the same, nip rolls for controlling the point of yarn twist supported by said deck and above the same, a yarn supply package also supported by said deck and laterally spaced from said nip rolls, a trough for containing liquid to be applied to the yarn of greater lateral dimension than the space between said rolls and said yarn-supply package, and an upright standard supporting said trough at a height substantially above said rolls and yarn supply package and directly above said space.
